W. H. BLAKE

POR TABLE LIGHTER

Filed June 11, 1927

Inventor
William H. Blake,
By Horatio E. Bellows

Attorney

UNITED STATES PATENT OFFICE.

WILLIAM H. BLAKE, OF ATTLEBORO, MASSACHUSETTS, ASSIGNOR TO JAMES E. BLAKE CO., OF ATTLEBORO, MASSACHUSETTS, A CORPORATION OF MASSACHUSETTS.

PORTABLE LIGHTER.

Application filed June 11, 1927. Serial No. 198,066.

My invention relates to portable or pocket lighters of the type wherein a fuel supplied wick is ignited by cooperating abrading and pyrophoric elements.

5 The essential objects of my invention are to produce the spark automatically rather than manually; to maintain the abrading element stationary relatively to the flint or pyrophoric element; to facilitate the substitution of abrading elements; to utilize the wick carrying member in elevating the operating arm; to facilitate the locking and release of the operating arm; to utilize said arm as a receptacle for the pyrophoric element and its impelling mechanism; and to attain these ends in a simple, convenient, and inexpensive structure.

To the above ends essentially my invention consists in such parts and combination 20 of parts as fall within the scope of the appended claims.

In the accompanying drawings which form a part of this specification

25 Figure 1 is a side elevation of my lighter closed showing parts broken away and parts in vertical central section,

Figure 2, a partial side elevation of the same in open position, showing parts in central vertical section,

30 Figure 3, a top plan view of the closed lighter,

Figure 4, a section on line 4—4 of Figure 3,

35 Figure 5, a fragmentary side elevation of the upper portion of the same, one of the journal ears being broken away, and

Figure 6, an elevation similar to that of Figure 5, but showing the operating arm elevated.

40 Like reference characters indicate like parts throughout the views.

The casing or body of my igniter may be of any form most convenient for carrying the operating parts. In the form thereof herein shown the hollow body 9 is of rectangular cross section and vertically elongated and forms a fuel chamber 10. The top 12 has a threaded opening 14 to engage the threaded upper portion 16 of a tubular guide 17 whose upper extremity has a closure 18 and a closure 19 resting upon the body top 9. A detachable cap 20 is attached to the lower end of the tube either frictionally, or by threads 22 and 23 upon the tube and side of the cap respectively.

A perforation 24 in the bottom of the cap loosely receives therethrough a wick tube 26 which projects also loosely through a perforation 27 in the top of the guide 17. Since the perforations 27 and 24 are of less 60 diameter than that of the guide 17 there is a resulting annular space 29 in which is a helical spring 30 having one end resting upon the cap 20 and its other end abutting against an annular shoulder 31 upon an intermediate portion of the tube 26. This shoulder also serves as a stop cooperating with the closure 18 to limit the upward travel of the wick tube under the impulse of the spring. There is a second annular shoulder 33 supported upon the wick carrying nipple 34 threaded in the outer end of the wick tube 26. A wick 35 frictionally engaged in the tube and nipple depends from the lower end thereof into the chamber 10. 75

Integral with the top of the casing, or fixed thereto in any convenient manner, is an elevation or block 37 having vertically disposed lateral ears or bearings 39 provided with central perforations 40 to receive a 80 tubular pin or pintle 42 having flanged over ends 43. This pintle traverses a hole 45 through a steel sparking or friction segment 47 whose flat lower face or peripheral portion 48 rests upon or is fixed to the elevation 37, as shown in Figure 2. The curved or major portion of the segment's periphery is provided with saw teeth or other serrations 49. It will be noted that the serrated member 47 is rigidly mounted, that 90 is to say is not circularly movable.

The member carrying the flint or pyrophoric element is a tubular arm indicated generally by 51. In this instance the arm comprises an outer tubular casing 53 of enlarged diameter at its outer end, as at 54, and closed by an end wall 55 provided with a central perforation 56. An intermediate portion of the arm has an elliptical opening 58 bounded by a depending flange 59. The inner end 60 of the casing 53 is slightly flattened laterally and substantially circular. The rear and bottom portions of the part 60 are cut away or bifurcated, forming ears 61. The latter are provided with oppositely disposed oblong longitudinal slots 62, as shown in Figures 5 and 6, through which loosely pass the pintle 42 by which the arm is pivotally mounted. The arm portion 60 forms a partial housing for the element 47, while 105 110

the ear portions 61 slidably engage the ears 39. Fixed by friction, solder, or otherwise in the casing 53 longitudinally thereof is a guide tube 64 whose outer end registers in 5 the perforation 56, and whose inner end terminates at a point adjacent the casing portion 60. In the latter end of the tube and projecting therefrom is slidably mounted a flint or pyrophoric member 66 pressed into 10 contact with the segment serrations 49 by a helical spring 68 in the tube engaging said member at one end, and pressing at its outer end against the threaded shank 69 of an adjusting screw 70. The outer end of the tube 15 64 is threaded, as at 72, to receive said shank, and the head 74 of the screw 70 is rounded. By turning this head the pressure of the element 66 upon the element 47 may be increased or diminished. When the arm is 20 depressed the flange 59 registers with the shoulder 33 and the wick 35 enters the opening 58.

A catch member for the operating arm is provided and comprises a post 76 fixed to 25 the top of the casing terminating in a rearwardly directed cam projection 77 having a vertically inclined top face 78, and a horizontal bottom face 79. This cooperates with a perforation 81 in the hollow portion 54 of 30 the operating arm. By reason of the elongated slots 62, when the arm is depressed and is passing down over the inclined face 78 of the cam the arm has a rearward longitudinal movement, but when the arm has 35 reached the face 79 the spring 68 snaps the arm back into locked position below the latter face.

To operate my device, the parts being in 40 the positions shown in Figure 1, the operator presses his thumb against the face of the element 74 of the arm 51 which releases the latter from the catch, whereupon the arm is violently impelled upwardly and rearwardly in an arc by the impulse of the 45 spring 30 which elevates the wick tube 26. The movement of the element 66 over the element 47 induces sparks which ignite the exposed end of the wick 35. The open position is shown in Figures 2 and 6. To lock 50 the parts, the arm 51 is downwardly pushed

thereby depressing the wick tube 26 and occluding, within the arm opening 58, the flame of the wick.

I claim:—

1. A portable lighter comprising a casing, 55 a tube yieldingly mounted in the casing and projecting therefrom, an ignitable element in the tube, a non-rotatably friction element and means for igniting said ignitable element including a swinging arm engageable 60 with the tube.

2. A portable lighter comprising a casing, 55 ignition means upon the casing including a pivoted arm and a non-rotatable friction element, a tube slidably mounted in the casing abutting against the arm, an ignitable element in the tube, and a spring engaging the tube for rotating the arm.

3. A portable lighter comprising a casing, 70 ignition means upon the casing including a pivoted arm provided with an opening, a non-rotatable friction element, a tubular guide housed in the casing, a cap upon the inner end of the guide provided with a perforation, a tube slidably mounted in the 75 guide and projecting from the tube engageable with the arm, an ignitable element in the tube extending through the perforation registerable in said opening, and a compressible spring in the cap supporting the 80 tube.

4. A portable lighter comprising a casing, 85 ears carried thereby, a friction element non-rotatably supported in the casing between the ears, a pintle in the ears, a hollow arm provided at one end with oblong longitudinally disposed slots in which the pintle is 90 slidable, and provided in its opposite end with a perforation, a pyrophoric element in the arm engaging the friction element, a spring in the arm engaging the pyrophoric element, a catch member rigidly mounted upon the casing provided with a cam face registerable in the perforation, and a yieldable member slidably mounted in the casing 95 abutting against an intermediate portion of the arm.

In testimony whereof I have affixed my signature.

WILLIAM H. BLAKE.
